DESIGN FOR A CASING FOR DRY CLEANING MACHINES

Peter Schladermundt, Bronxville, N. Y., and Charles L. Metzler, Palisades Park, and Elvin E. Hallander, West Caldwell, N. J., assignors to International Projector Corporation, Bloomfield, N. J., a corporation of Delaware

Application September 11, 1948, Serial No. 148,553

Term of patent 14 years

(Cl. D49—1)

To all whom it may concern:

Be it known that we, Peter Schladermundt, a citizen of the United States of America and a resident of Bronxville, in the county of Westchester and State of New York, Charles L. Metzler, a citizen of the United States of America, and a resident of Palisades Park, in the county of Bergen and State of New Jersey, and Elvin E. Hallander, a citizen of the United States of America and a resident of West Caldwell, in the county of Essex and State of New Jersey, have invented a new, original, and ornamental Design for a Casing for Dry Cleaning Machines, of which the following is a specification, reference being had to the accompanying drawing, forming a part thereof.

We claim:

The ornamental design for a casing for dry cleaning machines, as shown.

PETER SCHLADERMUNDT.
CHARLES L. METZLER.
ELVIN E. HALLANDER.
